UNITED STATES PATENT OFFICE.

DOROTHY E. RICHARDS, OF HAMILTON, ONTARIO, CANADA.

DESIGN FOR A GLOVE.

No. 39,609.

Specification for Design.

Patented Oct. 6, 1908.

Application filed June 8, 1908. Serial No. 437,465. Term of patent 3½ years.

To all whom it may concern:

Be it known that I, DOROTHY EDNA RICHARDS, a citizen of the Dominion of Canada, residing at No. 80 John street north, in the city of Hamilton, in the county of Wentworth, in the Province of Ontario, Canada, have invented a new, original, and ornamental Design for Gloves, of which the following is a specification, reference being had to the accompanying drawing, forming part thereof in which—

Figure 1, represents the back of the glove. Fig. 2, is a front view of the same.

As shown in the drawings my design consists of the ornamental design of a lady's fingerless arm glove, in which *a*, is the arm portion, *b*, *c*, *d*, the outer rounded hand portions,

the center one *d*, extending farther outwards than the other two; *g*, represents the stitching around the outer edge of the hand portion; *h*, represents the stitching at the back in three rows, and *e*, the oval finger loop attached to the central rounded projection *d*, for the insertion of the middle finger.

I claim:

The ornamental design for a glove as shown and described.

Hamilton, Ontario, Canada, April 30th 1908.

DOROTHY E. RICHARDS

Signed in the presence of—

G. NICHOLSON,
W.M. BRUCE.
